UNITED STATES PATENT OFFICE.

WALTER B. NUTTER, OF SCARBOROUGH, ASSIGNOR OF ONE-HALF TO FREDERIC C. BRIDGHAM, OF CAPE ELIZABETH, MAINE.

CAN-OPENER.

SPECIFICATION forming part of Letters Patent No. 373,412, dated November 15, 1887.

Application filed February 18, 1887. Serial No. 228,105. (Model.)

To all whom it may concern:

Be it known that I, WALTER B. NUTTER, a citizen of the United States, residing at Scarborough, in the county of Cumberland and State of Maine, have invented a certain new and useful Improved Can-Opener, of which the following is a specification.

The object of my invention is to provide a device by means of which cans of tin-plate or other thin sheet metal may be opened more readily and conveniently than can be done by the devices now in use.

My device is constructed as described in the following specification and illustrated in the accompanying drawings, which are hereby made a part of this specification, in which—

Figure 1 is a perspective view of my device. Fig. 2 is a side elevation of my device, with the jointed band for holding the can in position closed. Fig. 3 is a top plan view of the same, with the jointed band closed and the cam-headed lever, which secures the band when in the position shown in Fig. 2, closed.

Same letters show like parts in all the figures. At A is shown a clamp for attaching the device to the edge of a table or a bench, which may be done conveniently by a thumb-screw passing down through the upper part of the clamp and bearing upon the edge of the table or bench.

B is the circular plate firmly attached to and integral with the standard M, connecting it with the clamp A, this standard M being integral with A. At a upon the plate B is pivoted the arm C, and at the end of C, opposite to the pivot a, is the slot x and the engaging-stud y, and at b on C the lever D is pivoted, and upon the short arm of D the knife E is shown, having two edges, one upon each side, and having the barb c, as shown, which is also double-edged, the long arm of the lever D having the handle d for the convenience of being grasped by the operator. When the handle d is moved toward the clamp A, Fig. 3, the stud y strikes the end of x and C and D are very nearly in a straight line, and the knife E is then in position near enough to the central pivot a to cut through the side of the can; but when d is moved away from A the stud y moves along the slot x (which is segmental in form to

permit this movement) to the end of x away from A. The levers C and D are at an obtuse angle with each other, but still continuous in operation, from the central pivot, a, and this motion continued carries the knife E on the end of D back to the point where it is to begin its cut, but thrown out of the line of its cut in the passage backward. In the movement which puts C and D at an obtuse angle to each other D turns on the pivot b.

At F, Fig. 3, is shown the lever pivoted at f, this lever F having the cam g at its end. The parts F, G, H, and I form together a jointed band for encircling the can and holding it firmly in place while the top is being cut in the manner hereinafter described. The parts F and G and H and I are jointed by a joint between each pair, and form a continuous band to encompass the can, as follows: The part I is provided with the stud h, by which, when the parts F, G, H, and I are brought together around the body of the can, a slot in G is engaged, and F being thrown inward by the operation of the cam g against the stud h, the several parts are drawn firmly around the can, holding it firmly in position. When C and D are in such position (which will bring them in nearly a straight line from the pivot a) that the engaging-stud y presses against the end of the slot x toward the clamp A, and the lever D moved toward the clamp A, this motion makes the two parts C and D a continuous lever operating from the central pivot, a, the resistance being the operation of the knife in cutting the tin, the motion being in the direction to press the stud y against the end of the slot x; but if the motion is in the opposite direction the lever D will turn upon the pivot b and out of line with C. The slot x is in the form of a segment of a circle to permit the free movement of the stud y throughout its whole length.

The knife E has two sharp edges, one upon each side of the curved point, and the first motion of the operator in cutting after the can has been put in position, as hereinbefore described, is to grasp the handle d firmly with the fingers of the right hand and put the ball of the thumb against the side of D, bringing C and D into line with each other, during

which motion the stud *y* entirely traverses the length of the segmental slot *x*, which motion of the levers advances the knife *E* against the can, and at the same time gives a rocking cut 5 to the convex edge of the knife, this cut being continued until the incision is long enough to allow the point of the knife to pass through the side of the can, the cut thus far being made with the convex curve of the knife *E*. *C* and 10 *D* having now come in line with each other, they are so retained by the stud *y* in the slot *x*, and the levers *C* and *D* now operating as one on the pivot *a*, the knife cuts the tin with the concave edge quite around the can, or nearly 15 so. The general shape of the knife *E*, as shown, is made necessary by the requirement of having the outer convex edge of the knife an arc of sufficient length to make the first cut, as above described.

20 The operation of my invention is as follows: The can to be operated upon is placed with the end which it is desired to remove uppermost within the parts *F*, *G*, *H*, and *I*, with the upper end of the can against the plate *B*. The 25 slot *k* is put over the stud *h*, and by turning the lever or part *F* the cam *g* presses against *h*, and the can is thus held firmly in position for opening. The operator then grasps the handle *d* of the lever *D*, which turns upon its 30 own pivot *b*, and the knife *E* is thus thrust through the tin, cutting backward until the point of the knife has cut quite through the tin. The levers *D* and *C* then operate together, with the slot *x* and the engaging-stud 35 *y* engaged as one lever from the central pivot, *a*, and is brought around from right to left, the knife cutting its way through the side of the can and nearly quite around it, leaving but a very narrow strip of the tin uncut. The knife

being upon the end of the lever *D*, and this 40 lever being pivoted to the under side of *C*, the knife is thus brought below the end of the can to cut at the proper point for opening.

I am aware of Letters Patent to W. M. Bleakley, No. 95,873, for improvement in can-openers, dated October 19, 1869, and I claim none 45 of the devices described therein. In the use of my invention the can is not punctured to form a fulcrum for the lever carrying the knife; the can to be opened is not held in the hand of 50 the operator, but by the device itself, while the cut is made, and my device has the advantage of the very powerful leverage of *D* turning upon the pivot *b* to make the hardest cut—that is, the first puncture of the metal of 55 the can.

What I claim as my invention, and desire to secure by Letters Patent of the United States, is—

1. In a can opening device, as herein described; the jointed hinged band provided with the cam-headed lever *F*, engaging with the stud *h*, substantially in the manner and for the purposes set forth. 6c

2. In a device for opening cans, the combination of the two-part lever *C* and *D*, pivoted to the central plate at *a*, the two parts being pivoted at *b* and provided with the slot *x* and stud *y*, with the knife *E*, substantially in the manner and for the purposes set forth. 65

3. The improved can-opener consisting of the plate *B*, arm *C*, lever *D*, knife *E*, lever *F* and its parts *G*, *H*, and *I*, substantially in the manner and for the purposes set forth. 70

WALTER B. NUTTER.
